UNITED STATES PATENT OFFICE.

ALVAH BUSHNELL, JR., OF PHILADELPHIA, PENNSYLVANIA.

EXPANDING FILING-POCKET.

1,373,222.

Specification of Letters Patent. Patented Mar. 29, 1921.

Application filed November 15, 1919. Serial No. 338,166.

To all whom it may concern:

Be it known that I, ALVAH BUSHNELL, Jr., a citizen of the United States, residing at Philadelphia, in the county of Philadelphia and State of Pennsylvania, have invented new and useful Improvements in Expanding Filing-Pockets, of which the following is a specification.

My invention relates to new and useful improvements in filing wallets or cases, expanding envelops, paper pockets and the like, and has for its object to provide a truss for the bellows fold of such devices to prevent or reduce to a minimum the likelihood 10 of the wall formed by the bellows fold from projecting outside of the others or its inclosing walls.

More particularly the object of the invention is to provide a truss for an inwardly 20 foldable bottom of flexible filing devices or containers to prevent sagging thereof due to the weight of objects which it supports; and also to provide a truss for each of the end bellows folds of such a container so as to 25 limit the outward movement of such ends.

Another object of the invention is to provide an expandible wallet, filing case or 30 pocket with end flaps or wings secured to one of the sides to permit expansion of the wallet or case.

A further object of the invention is to provide in a device of the character stated 35 flexible end flaps or wings carried by a side wall and slidably registering with a chamber or pocket in the other side wall, said end flaps or wings having non-flexible ends to prevent their accidental withdrawal from the pocket or chamber.

A still further object of the invention is to 40 stiffen the end flaps or wings throughout the major portions of their length at their inner ends to prevent accidental withdrawal from the pocket in which they are inserted and to strengthen the upper edges of said 45 flaps.

With these ends in view, this invention 50 consists in the details of construction and combination of elements hereinafter set forth and then specifically designated by the claims.

In order that those skilled in the art to which this invention appertains, may understand how to make and use the same, I will describe its construction in detail, referring

by numerals to the accompanying drawings 55 forming a part of this application, in which:—

Figure 1, is a fragmentary perspective view of a filing case or expanding wallet in a relatively closed position embodying my 60 improvements, a portion of the end flap being broken away to plainly illustrate the construction.

Fig. 2, is a similar view showing it open or expanded. 65

Fig. 3, is a perspective view of a filing folder or simple filing case without end walls.

Fig. 4, is a section through the truss at the line 4—4 of Fig. 2, the thickness of the 70 walls being exaggerated.

Fig. 5, is a similar view at the line 5—5 of Fig. 2, above the truss.

Fig. 6, is an inner face view on a reduced scale of the filing case opened and 75 laid out flat,

Fig. 7, is an edge view thereof.

Fig. 8, is a fragmentary perspective view showing a modified form of the end walls in which they are of bellows form having 80 a stiffening strip or truss superimposed thereon.

Fig. 9, is an edge view of one of the bellows sections showing a modified arrangement for trussing or stiffening the same. 85

Fig. 10, is a view similar to Fig. 9 showing a further modified form of truss as applied to a bellows fold.

In carrying out my invention as here embodied, 2 and 3 represent the two sides or 90 side walls of a filing case or wallet or similar device, the side 2 generally being the back and the side 3 the front. These sides are connected by an inwardly foldable or bellows bottom 4 having a bend or crease 5 95 to permit expanding and collapsing thereof.

To prevent the bottom from sagging, dropping down or projecting below the lower edges of the sides, when supporting papers or other objects placed in the filing 100 wallet or case and which would increase the height of the filing case, I provide a truss 6 which is securely attached to the inner face of the bottom on each side of the crease 5 but is free from the bottom in the 105 region of the said crease. The truss is also provided with a crease 7 which overlies the crease 5 but is spaced therefrom because of

the arrangement of the truss which is wider between the same two points. The truss is produced from the material forming a portion of one side of the filing case or from 5 material attached only to the bottom. This truss may be left free from the bottom throughout its entire or major portion of its length yet serve the same purpose as that just described.

10 The material forming the truss may be attached in any suitable manner but as filing cases of this character are generally made of paperoid, cardboard, paper and similar materials, a suitable adhesive is usually and 15 advantageously employed.

As shown in Figs. 1, 2 and 4 to 7 inclusive, one of the sides as 2, is provided with end flaps or wings 8, the free ends of which slidably or adjustably engage the other side 20 3, said side preferably being provided with a chamber or pocket 9.

The end flaps or wings 8 are flexible throughout a portion of their length, said flexible portion being sufficient to extend 25 from one side to the other when the filing case is fully expanded, while the free ends which slide within the pocket are stiff and these stiffened ends should be longer than the flexible portions to prevent their accidentally 30 withdrawal from the pocket so that the major portions of said end flaps or wings are stiff.

In actual practice the side 2 which is used as the back is made of two thicknesses of 35 material 10 and 11 between which the end flaps or wings 8 are secured while the side 3 which becomes the front is made of two thicknesses of material 12 and 13 throughout a portion of its height only, one of said 40 thicknesses of material extending from the bottom to a point intermediate the upper and lower edges of the side 3 leaving the upper portion of the side 3 of single thickness to form a flexible flap 14 which may 45 be easily and readily bent forward for insertion of papers or other articles in the filing case. The two sheets or thicknesses of material 12 and 13 are not attached to each other for a distance equal to the height 50 or width of the end flaps or wings so as to form the pocket 9 in which said end flaps slide.

The end flaps or wings 8 may be moved in and out of the pocket by inserting the 55 thumbs or fingers in the open ends of the pockets, but if found desirable openings 15 may be formed in the outer sheet or thickness of material 13 of the side 3, one adjacent each end so that the thumbs or fingers 60 may be pressed against the end flaps or wings to move them in either direction and this may be more readily accomplished if the thumbs or fingers are dampened slightly.

The free or sliding ends of the end flaps 65 or wings 8 are stiffened by attaching there-

to an additional sheet of thickness of material 16 which should extend throughout the major portion of their length to prevent them being accidentally withdrawn when in use. The edges of the end flaps or wings 70 8, particularly the upper edges may be strengthened by folding a portion of the material upon itself along the upper edges of said end flaps as indicated by the reference numeral 17, Fig. 6. By constructing the 75 end flaps in this manner the likelihood of their being torn in the filing case is reduced to a minimum.

By constructing an expanding filing case 80 in the manner above described it is relatively inexpensive in the cost of manufacture as it eliminates the bellows end walls and skilled or experienced workers are not required to produce them. This construction also provides an exceedingly strong 85 and durable filing case which cannot be expanded beyond the limits of the flexible portions of the end flaps or wings and provides a bottom which will not sag under the weight of the ordinary articles generally 90 placed in such filing cases.

Where it is desirable the flaps or end walls may be made in the form of bellows folds as indicated at 23, Fig. 8, and these folds may be trussed in the same manner 95 as above described in connection with the bottom of the filing case or they may be reinforced by a layer of material 24 superimposed thereon or forming a part thereof and by slightly scoring the inner surface of 100 this superimposed material or breaking the same the effect of a butt joint is produced and therefore these ends will be prevented from being forced outward beyond the front and back walls of the container by the papers which may be filed therein. 105

In Fig. 9 I have shown the form of joint just described in connection with Fig. 8, while in Fig. 10 a slightly modified form 110 of the same is shown in which two separate pieces of material are superimposed and secured upon the bellows fold 23, and the meeting ends of these strips of material are adapted to abut and thus limit the outward movement of this bellows fold. While I 115 have shown this modified form of bellows fold as applied to the end walls of the container it is obvious they may be utilized for the bottom thereof.

Of course I do not wish to be limited to 120 the exact details of construction as herein shown, as these may be varied within the limits of the appended claims without departing from the spirit of my invention.

Having thus fully described my invention 125 what I claim as new and useful is:—

1. A filing case comprising sides, a bottom having a crease so as to fold inward and a truss attached thereto at each side of, 130 the crease.

2. A filing case comprising sides, a bottom having a crease so as to fold inward, a truss attached thereto at each side of the crease, and free therefrom in the region of 5 said crease.
3. A device of the character described comprising sides, a bottom having a crease, a truss having a crease, attached to the inner face of the bottom at each side of the 10 crease in said bottom and free therefrom in the region of said crease, said truss being wider between its points of attachment than the bottom between the same points.
4. A filing case or wallet comprising side 15 walls, an inwardly foldable bottom connected with said side walls, a truss on said bottom to prevent sagging thereof, and end flaps or wings carried by one of the sides and slidably engaging the other side to permit expansion of the filing case.
5. A filing case comprising side walls one 20 of which is provided with a pocket, an inwardly foldable bottom connected with said sides and a truss carried by the bottom, and end flaps or wings carried by one of the sides and slidably registering with the pocket in the other side.
6. A filing case comprising side walls one 25 of which is provided with a pocket, an inwardly foldable bottom connected with said sides and a truss carried by the bottom, and end wings or flaps flexible throughout a portion of their length but having a non-flexible free end, said flaps or wings carried 30 by one of the sides and slidably registering with a pocket in the other side.
7. A filing case comprising sides one of 35 which is provided with a pocket, an inwardly foldable bottom connected with said sides, a truss carried by said bottom to prevent sagging thereof, end flaps or wings carried by one of said sides and adjustably registering with the pocket in the other side, and means for stiffening the free ends of 40 said end flaps or wings.
8. A filing case comprising sides one of 45 which is provided with a pocket, an inwardly foldable bottom connected with said sides, a truss carried by said bottom to prevent sagging thereof, end flaps or wings carried by one of said sides and adjustably registering with the pocket in the other side, and a stiffener attached to the free end of 50
- each of said end flaps and extending throughout the major portions of said flaps. 55
9. A filing case or wallet comprising sides, one of said sides having a pocket therein provided with openings communicating with said pocket, an inwardly foldable bottom connected with said side walls, a truss 60 connected with said bottom to prevent sagging thereof, and end wings having non-flexible free ends carried by one of the sides and slidably entering the ends of the pocket.
10. A filing case or wallet comprising a 65 back side wall formed of two thicknesses or sheets of material, end wings or flaps secured between said sheets or thicknesses of material, said end wings or flaps formed of two sheets or thicknesses of material 70 throughout the major portions of their length adjacent their free ends, a front side formed of two thicknesses or sheets of material throughout a portion of its height leaving the upper end of one sheet or thickness of material, said sheets or thicknesses of material being free from each other for a distance equal to the height of the end flaps or wings to form a pocket therefor in which said end flaps are slidably located 75 from which accidental withdrawal is prevented by the stiff ends thereof one of the sheets or thicknesses of material having openings therein communicating with the pocket whereby the end wings may be moved inward or outward, an inwardly foldable bottom connected with said sides, said bottom having a crease therein, and a truss attached to the inner face of said bottom in each 80 side of the crease free from said bottom in the region of its crease, said truss being wider between the two points of attachment to the bottom, than said bottom between the same two points. 85
11. In combination with a case or wallet 90 of the character described having bellows folds, and a truss consisting of a strip superimposed upon said bellows folds.
12. In combination with a wallet having 95 bellows folds, and a truss consisting of a strip superimposed upon but unattached to said bellows folds.
- In testimony whereof I have hereunto affixed my signature.

ALVAH BUSHNELL, JR.
